UNITED STATES PATENT OFFICE.

PAUL WIEGHARDT, OF MAGDEBURG, GERMANY, ASSIGNOR TO THE FIRM: FRIED. KRUPP GRUSONWERK AKTIENGESELLSCHAFT, OF MAGDEBURG-BUCKAU, GERMANY.

VERTICAL LEAD-CABLE PRESS.

Application filed December 31, 1926, Serial No. 158,368, and in Germany February 19, 1926.

This invention relates to vertical lead cable presses, and more particularly to the fitting of tool holders therein. It is necessary that the press heads of vertical lead cable presses should be made in two parts so as to be able to machine the conduits which guide the lead admitted from the top into the press head in such a manner that it escapes horizontally between the mandrel and the matrix in the form of a lead covering. This necessity involves the drawback that the tool holders, which hitherto have been screwed into the press head, either get their screw threads damaged owing to the division of the tapped thread in the press head, or, in their turn, damage the said tapped thread if the threads do not agree or coincide exactly. Such want of exact coincidence or agreement of the threads occurs, according to experience, after a certain time of working, as the operation of a lead cable press results in the press head being exposed to considerable variations of temperature which in the course of time result in warping; a change of shape of the press head is also produced owing to the high pressure in the interior. The warping and changes of shape, even though they are slight, lead, owing to the heavy stresses on the threads, to damage to the thread or even to a complete destruction of single threads, or of the whole of them, by breaking. These drawbacks occur more particularly in the thread of the mandrel holder and in the corresponding tapped thread of the press head, as the working of the press makes it necessary to force the mandrel into the lead contained in the press head by means of the mandrel holder, for the purpose of determining the correct thickness of wall of the lead covering.

According to this invention the above mentioned drawbacks are avoided by inserting in the divided press head one or more sleeves, each made in one piece, into which the tool holders are screwed.

By way of example, the accompanying drawing shows the press head of a vertical lead cable press embodying the present invention: in the drawing

Figure 1 is a vertical section of the press head through the axis of the tool holders, and Figure 2 is a plan of the bottom portion of

the press head with the tool holders in section.

In the construction illustrated recesses in the two portions 1 and 2 of the press head accommodate a screw-threaded sleeve 3 provided with a collar 4, which, as indicated, may be midway of its length, and occupies an annular groove 5. The sleeve 3 is so dimensioned as to leave a slight space between its external surface other than that of the collar 4 and the recesses which accommodate it, and its rotation relatively to the press head is prevented by means of a key 6. The mandrel holder 7 is screwed into the sleeve 3 and the matrix holder 8 could also be mounted in a similar sleeve in one piece.

The construction of the sleeve above described, which could be modified to prevent longitudinal or rotational motion in any desired manner, has the further advantage that the sleeve can expand or contract independently of the press head. A contraction of the sleeve takes place for instance when the tool holders (during the changing of the tools) are withdrawn, and the sleeve is cooled by the surrounding air. This contraction of the sleeve is very desirable and advantageous because the dismantled tool holders are also cooled and therefore contract. When reinserting the tool holders, there is therefore a probability that the tools and the screw-threaded sleeves will have approximately the same temperature. In any case, however, the sleeve will assume, after a relatively short time, the temperature of the tool holder, as it is in thorough contact with the latter, whilst it is in contact with the press head only by means of the relatively narrow collar 4. This equalization of temperature between the tool holder and sleeve results in all the threads of the tool holder and of the sleeve bearing in a uniform manner. This is of great importance as the guarantee against damage to the thread, already provided by the making of the sleeve in a single piece, is further strengthened. The space between the bushing 3 and the press head can be filled with a heat insulating material, such as asbestos or the like.

What I claim is:

1. A vertical lead cable press having a divided press head the division surfaces of

which lie parallel to the tool holder axis, the two parts of said press head having recesses, a one piece sleeve non-rotatably mounted in said recesses, and a tool holder threaded in

adapted to receive said collar, the surface of said sleeve, with the exception of said collar, being separated from the walls of said recesses.

5 said sleeve.

2. A vertical lead cable press as in claim 1 characterized by the fact that said sleeve is provided with a circumferential collar and said recesses are provided with grooves

The foregoing specification signed at Berlin, Germany, this 17th day of December, 15
1926.

PAUL WIEGHARDT.
